UNITED STATES PATENT OFFICE

135,437

DESIGN FOR A CAP

Paul M. Maxwell, Manhasset, N. Y., and Wilhelmina J. Russy, Jersey City, N. J., assignors to Hat Corporation of America, Norwalk, Conn., a corporation of Delaware

Application July 3, 1942, Serial No. 107,400

Term of patent 7 years

To all whom it may concern:

Be it known that we, Paul M. Maxwell and Wilhelmina J. Russy, citizens of the United States, residing, respectively, at Manhasset, county of Nassau, and State of New York, and at Jersey City, county of Hudson, and State of New Jersey, have invented a new, original, and ornamental Design for a Cap, of which the following is a specification, reference being had to the accompanying drawing, forming a part thereof, and in which:

Fig. 2 is a rear view thereof.

Fig. 3 is a side view of the cap shown in Fig. 1.

Fig. 4 is a top view thereof.

The design of the cap disclosed is characterized by the configuration, proportions and arrangement of its component parts specifically as shown.

We claim:

The ornamental design for a cap, as shown and described.

PAUL M. MAXWELL.
WILHELMINA J. RUSSY.
